US00D737796S

(12) **United States Design Patent**
Liu

(10) **Patent No.:** US D737,796 S
(45) **Date of Patent:** ** Sep. 1, 2015

(54) **WIRELESS HEADSET TRANSCIEVER WITH CLIP**

(71) Applicants: **LITE-ON ELECTRONICS (GUANGZHOU) LIMITED, Guangzhou (CN); LITE-ON TECHNOLOGY CORPORATION, Taipei (TW)**

(72) Inventor: **Liang-Yi Liu, Taipei (TW)**

(73) Assignees: **LITE-ON ELECTRONICS (GUANGZHOU) LIMITED, Guangzhou (CN); LITE-ON TECHNOLOGY CORPORATION, Taipei (TW)**

(**) Term: **14 Years**

(21) Appl. No.: **29/482,777**

(22) Filed: **Feb. 21, 2014**

(30) **Foreign Application Priority Data**

Jan. 6, 2014 (TW) 103300081

(51) **LOC (10) Cl.** 14-01

(52) **U.S. Cl.**

USPC **D14/205**

(57) **CLAIM**

The ornamental design for a “wireless headset transceiver with clip,” as shown and described.

DESCRIPTION

FIG. 1 is a perspective view of a wireless headset transceiver with clip showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view viewed from another visual angle thereof.

The broken lines depict portions of the wireless headset transceiver with clip which form no part of the claimed design.

1 Claim, 7 Drawing Sheets
